BEST AVAILABLE COPY

A1
№167

2. Piedmont

Smoke Machine.

A. P. Patented June 23, 1857.

No. 167, to original Letters Patent No. 13,731.—For Spoke and Axe-helve Machine.—I claim the jointed guides having slots c d e, in combination with the slots f g h of the bed, and bolts securing said guides to the bed; the aforesaid slots having the relative position hereinbefore set forth:

OWEN REDMOND